(57) **CLAIM**

The ornamental design for the paper towel holder, as shown and described.

DESCRIPTION

FIG. 1 is a left side elevation view of a paper towel holder showing our new design, the side opposite being a mirror image thereof;

FIG. 2 is a front view thereof, the side opposite being a mirror image thereof;

FIG. 3 is a left side view thereof, the side opposite being a mirror image thereof;

FIG. 4 is a top plan view thereof; and

FIG. 5 is a bottom plan view thereof.

FIGS. 6 to 10 illustrate an alternate embodiment, showing a contrast in materials using stippling to differentiate between areas of the Paper Towel Holder illustrated in FIGS. 1 to 5, whereas:

FIG. 6 is a detailed left side elevation view of the alternate embodiment, the side opposite being a mirror image thereof;

FIG. 7 is a detailed front view thereof, the side opposite being a mirror image thereof;

FIG. 8 is a detailed left side view thereof, the side opposite being a mirror image thereof;

FIG. 9 is a detailed top plan view thereof; and,

FIG. 10 is a detailed bottom plan view thereof.
